UNITED STATES PATENT OFFICE.

MILFORD T. VANDERVOORT, OF GRAND RAPIDS, MICHIGAN, ASSIGNOR TO ABRAHAM VANDER HENST, OF GRAND RAPIDS, MICHIGAN.

FUEL-PASSAGE LOCK FOR INTERNAL-COMBUSTION ENGINES.

Application filed March 21, 1921. Serial No. 454,016.

To all whom it may concern:

Be it known that I, MILFORD T. VANDERVOORT, a citizen of the United States of America, residing at Grand Rapids, in the 5 county of Kent and State of Michigan, have invented certain new and useful Improvements in Fuel-Passage Locks for Internal-Combustion Engines; and I do hereby declare the following to be a full, clear, and 10 exact description of the invention, such as will enable others skilled in the art to which it appertains to make and use the same.

This invention relates to a fuel passage lock for use with internal combustion engines. It is a primary object and purpose 15 of the present invention to provide a movable locking gate which may be operated across and close the passage for fuel between the carburetor and engine, said gate 20 when in operative position stopping any passage of fuel to the engine, thereby rendering operation of the engine impossible. A further object of the invention is to provide operation means for said locking gate 25 which may be actuated to either move the gate to operative fuel obstructing position, or moved to a different position whereby the gate may move by gravity to an inoperative position, thus allowing free passage of the 30 fuel. A still further object of the invention is to provide a simple, yet effective means for operating the locking gate, similar in operation to a combination lock which is manually turned back and forth to different 35 positions, being guided as to the amount to be turned in different directions by a numbered dial similar to and operated like the dial in combination locks, and operable at a distance from the fuel passage locking gate 40 whereby, for motor vehicle use, the dial operating means may be mounted on the dash of the vehicle and operated from the front compartment thereof. Various other objects and purposes than those enumerated, 45 all tending to simplicity of construction and economy in manufacture, will appear as understanding of the invention is had from the following description, taken in connection with the accompanying drawings, in 50 which,

Fig. 1 is an elevation showing my invention applied to the fuel conduit of an internal combustion engine.

Fig. 2 is a side view of the gate mechanism, one side of the casing therefor being

removed to show inner structure, and of the operating mechanism therefor, with parts broken away and in section for better disclosure.

Fig. 3 is a vertical section through the 60 fuel conduit and attached gate mechanism, showing the gate in lower inoperative position.

Fig. 4 is a like view showing the gate in 65 upper operative position.

Fig. 5 is an elevation of the inner cam member of the mechanism housed within the casing.

Fig. 6 is an edge view thereof.

Figs. 7 and 8 are elevations of the two 70 disk members housed within the casing one at either side of the cam member, and

Fig. 9 is an elevation of the gate.

Like reference characters refer to like parts in the different figures of the drawings.

The outlet to the carburetor is indicated at 1 in alignment with the lower end of the manifold 2 which leads to the engine cylinders as is well understood. Between the adjacent ends of the parts 1 and 2, the upper projecting portions 3 and 4 of two casing members are placed facing each other. Said casing portions 3 and 4 have laterally projecting ears 5 with openings therethrough 80 to align with similar openings in similar ears at the ends of parts 1 and 2, bolts 6 passing through the aligned openings for fixedly securing the carburetor outlet 1, manifold end 2 and parts 3 and 4 together. Said casing parts 3 and 4 have openings therethrough matching the passage through the manifold so that fuel can pass freely from the carburetor to the engine when the passage therefor is unobstructed. 85

Extending downwardly from each part 3 and 4 and integrally formed therewith are frames 7 and 8 from which outwardly projecting semi-cylindrical housings extend in opposite directions as indicated at 9 and 10. 90 A hollow and short cylindrical housing is made through which a short horizontal shaft 11 extends, being rotatably mounted at its ends in bearings 12 and 13 as shown in Fig. 2. A flexible shaft 14, housed within a tube 105

15 is connected at one end to shaft 11, leading at its other end to the dash 16 and through the same. A circular plate 17 is connected to the rear side of the dash over which a dial 18 is placed, the same having a 110

series of spaced-apart figures around it at its edge. The dial has an integral operating knob 19 through which a set screw 20 passes to connect the dial to a short shaft or pin 21 which is permanently connected to the other end of the flexible shaft 14. By turning the dial back and forth the shaft 11 may likewise be turned back and forth as is obvious.

A cam member 22 is connected to and turns with the shaft 11 within the hollow housing, being of the shape shown in Figs. 5 and 6 and having a projecting tongue 23 at one side and a pin 24 passing therethrough and extending a short distance to each side of the member. At one side of said cam member a disk 25 is located, loose on the shaft 11 and having a circular slot cut therein which extends nearly through the entire arc of the disk and with a radial slot cut inwardly in the disk between the ends of the circular slot. The radial slot is shown at 26 and the circular slot at 27. A second disk 28 having a like radial slot 29 and a curved slot 30 of shorter length than slot 27 is mounted loosely on the shaft 11 at the other side of the cam member 22. The ends of pin 24 pass into the slots 27 and 30. A leaf spring 31 is seated in the bottom of the housing and presses against the edges of the disks, normally keeping the same from moving.

The casing projections 3 and 4 are formed with a guide 32 for a gate 33 slidably mounted therein. The gate has a depression 34 in one side adapted to receive the tongue 23 of the cam member 22. This gate in upper position, shown in Fig. 4 closes the fuel passages and the engine cannot run when it is in such position. In its lower position, shown in Fig. 3, the passage is open for the free passage of the fuel to the engine.

The gate can come to its lower position only when the radial slots 26 and 29 are in alignment with the guide 32 and the cam member occupies the position shown in dotted lines in Fig. 3. By turning the knob 19 in one direction far enough pin 24 comes to the end of slot 30, thereafter carrying the disk 28 on further rotative movement of the knob and at one point bringing the slot 29 below and in alignment with guide 32. Where this point is determined by the position of the knob and dial on the shaft 21, and a certain number on the dial will indicate it when brought to proper position with reference to the plate 17. By turning the knob in the reverse direction, the pin then, after a partial revolution of shaft 11, engages with the disk 25 at the end of slot 27 and turns it so that its slot 26 aligns with the guide 32 when a second predetermined number on the dial coincides with an arbitrary stopping point on the disk 17. Then by turning the knob back until tongue 23 strikes against the gate 33 which has low-

ered into the two slots, the passage for fuel is open. The tongue 23 enters the recess 34 and holds the gate from any upward movement due to the motion of the motor vehicle on which it is installed. When it is desired to elevate the gate, it is merely necessary to turn the knob and dial and connected shaft 11 in the proper direction, the cam edge of member 22 riding under the lower edge of the gate and raising it to operative position as shown in Fig. 4, this at the same time turning the disks 25 and 28 away from position where their radial slots are in alignment with guide 32.

This construction is simple, may be made at low cost, either from patterns or from sheet metal with dies. The invention is defined in the appended claims and I consider myself entitled to all constructions comprehended by said claims.

I claim:

1. In combination with a carburetor outlet, a manifold in alignment therewith, a casing disposed between said outlet and manifold and secured thereto, said casing depending below the carburetor outlet and manifold and having an opening therethrough in alignment with the passages through the outlet and manifold, a gate slidably mounted in the casing to pass across said opening, a shaft rotatably mounted in and through the casing at a point below the gate, a cam attached to the shaft adapted to raise the gate into operative position on turning in one direction, a pin passing through the cam member, two disks loosely mounted on the shaft one each side of the cam member, each being provided with a curved concentric slot into which the ends of the pin pass, and with a radial slot wide enough to pass the gate and located in each disk between the ends of the curved slots, one of said curved slots in one disk being shorter than the other, and means to turn the shaft, substantially as and for the purposes described.

2. A construction containing the elements in combination defined in claim 1, combined with spring means frictionally engaging against the edges of the disks, substantially as described.

3. A construction containing the elements in combination defined in claim 1, combined with a flexible shaft connected to the first shaft, a dial and operating knob attached to the other end of the flexible shaft, and a plate over which the dial passes in turning, said dial having indicating characters thereon and said plate having an arbitrary stopping point bearing relation to the dial and said cam member and disks, substantially as and for the purposes described.

In testimony whereof I affix my signature.

MILFORD T. VANDERVOORT.
